AUXILIARY HOT AIR HEATER

Joseph Buckley, Methuen, Mass.

Application December 10, 1943, Serial No. 513,709

2 Claims. (Cl. 126—108)

This invention relates to devices for utilizing a greater percentage of the heat from a house heater in heating the house and in providing clean fresh hot air to the room or rooms thereof.

In steam and hot water systems, whether of the forced draft, oil or gas type, or the coal type, after heating the steam or the hot water it is conducted to the room or rooms to be heated while a large proportion of the heat produced escapes up the chimney as waste and is lost.

The main feature of my device is what I will call a secondary hot air heater, heated from the products of combustion from a primary heater, of such a character that a large part of the waste or exhaust heat is used in heating clean air which is conducted to a room or rooms to be heated.

It may be used with a primary hot air heater, a steam or hot water heater of any of the forced draft types or it may be used with primary heaters which are not of the forced draft type. It may also be used in the same enclosure with a primary heater or in a separate enclosure. It may also be used in connection with such heaters located in a cellar or basement or it can be used in connection with a primary heater of the direct type, such as a stove, both located in a room to be heated.

It is necessary to keep the clean air which is to be delivered to the room to be heated separate from the dirty or foul air containing the products of combustion from the primary heater and the main feature of my device is the provision of a receiving drum which is inside the enclosing shell for the clean hot air and which receives the products of combustion from a primary heater, and which on its inside has a removable drum which might be called a dead air or clean out drum, the parts being so arranged that when soot forms, this inside removable drum can be lifted up or out and it and the surrounding parts can then be easily and thoroughly cleaned.

The fundamental purpose of this device is to utilize the heat of the products of combustion from some primary heater by carrying them down around and between concentric drums or chambers positioned inside a clean hot air chamber with preferably the inside drum containing dead air or products of combustion while between the drums, the live products of combustion travel downward and then out after losing a large part of their heat to the clean air chamber.

Preferably I utilize the fact that with heat-

ing means of the forced draft type, such as used with oil and such as is produced by gas, it is not necessary to heat the chimney by the products of combustion to produce the draft. 5 However, my secondary hot air heater can be used with ordinary fuel and an ordinary fire pot provided with a heating dome.

The special features of my device are that the hot foul air and hot gases travel from a primary heater through a clean air chamber to the top of a secondary heater and in there, instead of going directly to a smoke outlet, they travel around an annular space between an outside drum and a concentric inside drum thereby distributing the heat to and utilizing it by conduction through the outside drum into the clean air chamber.

These concentric drums and this arrangement of inlets and outlets prevent the formation of 20 and break up any direct currents of the products of combustion which would waste heat.

At the same time the foul air is kept away from the clean air. Soot and dirt can settle on the bottom of the secondary drum but it and all 25 other parts including the clean air chamber can easily be reached for cleaning.

In the drawings,

Fig. 1 is a vertical sectional view as on the line 1—1 of Fig. 4.

30 Fig. 2 is a detail of one of the separating lugs and Fig. 3 is a detail of one type of burner for a primary heater.

Fig. 4 is a sectional view looking down on the irregular line 4—4 of Fig. 1.

35 Fig. 5 is an elevational view of another embodiment of my device.

Fig. 6 is a sectional view looking down on the irregular line 6—6 of Fig. 5.

40 Fig. 7 is a vertical sectional view as on the line 7—7 of Fig. 6.

Fig. 8 is a view similar to Fig. 7 of a modification.

In the drawings, 31 represents a floor which 45 as shown coincides with the ceiling of the basement B and with the floor of a room such as R to be heated and in which there may be a register 32 connected by a conductor C to a clean hot air chamber D.

Such a hot air chamber may have side walls 50 like 33 near the bottom of which are clean air inlets 35 and it may rest with its walls 33 on the basement floor 34.

As shown in Fig. 1, the top 36 of chamber D extends up over heater P and to the conductor C which ends at register 32 in floor 31. Top 36

over secondary hot air heater A has a clean out opening 39 on which rests a cover 6 with a handle 7.

As shown in Figs. 1 and 2, a primary hot air heater P positioned in chamber D may have a heating dome 10 with relatively thin metal walls 11 except at the bottom 12 where it is formed as a lined firepot. It may have a clean out door 13 and an opening 14 to receive the fire nozzle 4 from heating means F shown as of any common oil burning type having a casing 1, oil inlet 2, and blower fan 3 driven by any suitable motor, not shown, and which may or may not be controlled by any well known electric thermostatic control means.

Primary hot air heater P has an air and gas tight bottom 87 and the thin walled heating dome 10 which near its top has an outlet opening 19 for the products of combustion and for a smoke pipe connection S which connects it with a similar inlet opening 29 at the top of a secondary hot air heater A.

This secondary hot air heater A is of cylindrical or drum shape and includes an outside drum 22 with an air and gas tight bottom 37 and a removable cover 23 with a handle 17 and a concentric inside dead air drum 24 which rests on bottom 37 and which can be taken out of outside drum 22 by means of a handle 25 after lifting off the cover 6 of the clean hot air chamber D and cover 23 of drum 22.

Drum 24 is removable as a complete unit.

There may be settling holes 26, 26 in its top which allow a certain amount of products of combustion to settle on bottom 37 and prevent heated air in drum 24 from causing drum 24 to be lifted or to chatter when the fire is first started or heats up this drum unusually fast.

Drum 24 is spaced concentrically inside drum 22 by spacing lugs 20 held in place on drum 24 by screws 120 as shown in Fig. 2.

The whole inside of the clean hot air chamber and of the primary and secondary heater can easily be reached for cleaning by means of the removable covers 6 and 23, the clean out door 13, and clean out door 27 which closes or opens a passage 28 into drum 22 and by lifting out drum 24.

Bottoms 87 and 37 should be integral with or be connected by gas tight joints with the sides of primary heater P and secondary heater A respectively.

In place of an oil type of heater with a fan such as shown and described as heating means F, I can use a gas burner with a nozzle such as 8 shown in Fig. 3, which connects with the pressure gas supply of a city which, in the combustion chamber 80, is mixed with air entering through air holes 5 thus providing heat for the primary heating chamber P through opening 14.

As shown in Figs. 5, 6, and 7, I can use a rectangular clean hot air chamber such as G in which is a primary hot air heater H and a secondary hot air heater K.

Chamber G has four walls 40, 40, 40, 40, and as shown has a bottom 41 and is supported on legs 42, 42 there being a plurality of clean air inlets 43, 43, in the bottom. It is provided with a removable cover 44 which as shown, has an outside flange 45 which fits over the top of the walls 40, 40, 40, 40, the cover having clean air passages 74 to allow the heat to escape and also has a fire box 48 with a fire door indicated by 49 which closes a passage 47 through chamber G into primary hot air heater H with a bottom 10.

This primary hot air heater H may be heated by gas in a manner similar to what is shown in Fig. 3 or a range oil heating device of any well known construction including a burner 50 with feed pipe 51 running from a gravity tank 52 can be used. The air to be burned comes into the fire box 48 through the air holes 53, 53, in bottom 41, and air holes 71 in bottom 10 and out into secondary heater K through a smoke pipe 46.

The secondary heater K is similar in construction to A. It includes an outside drum 60 with thin metal walls 61 and a gas tight bottom 72 which rests on the bottom 41 of the device. It has a removable cover 62 and the inside dead air drum 63. This dead air drum 63 has a fixed cover 64 with air holes 65 and a handle 66. It can be removed as a unit in the same manner as the drum 24.

It is spaced from walls 61 of the outside drum 60 by lugs 68, 68.

In Fig. 8, I show a construction which can be used in connection with any smoke pipe such as L from any kind of a primary heater, the secondary heater N being interposed between the chimney and the heater as in a basement where there is a steam, hot water, coal or any other kind of a heater with a smoke pipe L. This smoke pipe L is conducted through clean air chamber 80 having a removable cover 81 and forms part of the primary heater. It has clean air inlets 86 near the bottom, a removable cover 81 and an outlet 88 to a register 89 in a floor 90.

The smoke pipe L enters near the top of drum 82 part of secondary heater N which includes this outside drum 82 with a removable cover 83 and an inside drum 84 which itself is removable, the products of combustion continuing down and between the two drums and out at the bottom through an exhaust pipe 85 as to a chimney.

I claim:

1. For use in supplying clean hot air to the rooms of a house having a basement; a hot air heating assembly adapted to be positioned in the basement and including an outer clean air shell forming a clean hot air chamber having clean air inlets proximate its lower part and a clean hot air outlet in its top part; a conductor from said clean hot air outlet to a room to be heated; a fire box including a heating dome forming a primary hot air heater with a smoke outlet near the top of the dome and being located within and spaced from the walls of the clean hot air chamber and being sealed from said clean hot air chamber; heating means for heating the fire box with a forced draft; a removable cover for part of the top of the clean hot air chamber; a secondary hot air heater including an outside drum spaced from the wall of the clean hot air chamber and having a removable cover under the cover of the clean hot air chamber, and a removable dead air drum having a perforated top and being inside the outside drum of the secondary hot air heater and concentrically spaced from the walls thereof; a smoke pipe connection between the fire box smoke outlet and the secondary heater near the top of both; and a smoke exhaust pipe from near the bottom of the space between the outside drum and the dead air drum of the secondary heater through the clean hot air chamber.

2. For use in supplying clean hot air to a house; a hot air heating assembly including an outer clean air shell forming a clean hot air chamber having clean air inlets proximate its lower part and a clean hot air outlet in its top part; a fire box including a heating dome forming a primary

hot air heater with a smoke outlet near the top of the dome and being located within and spaced from the walls of the clean hot air chamber and being sealed from said clean hot air chamber; a removable cover for part of the top of the clean hot air chamber; a secondary hot air heater including an outside drum spaced from the wall of the clean hot air chamber and having a removable cover under the cover of the clean hot air chamber, and a removable dead air drum having 10

5 a perforated top and being inside the outside drum of the secondary hot air heater and concentrically spaced from the walls thereof; a smoke pipe connection between the fire box smoke outlet and the secondary heater near the top of both; and a smoke exhaust pipe from near the bottom of the space between the outside drum and the dead air drum of the secondary heater through the clean hot air chamber.

JOSEPH BUCKLEY.
